CAMERA WITH SELF-CONTAINED STROBE LIGHT

Ronald Emmerling, New City, N.Y., assignor to
Berkey Photo, Inc., Paramus, N.J.

Filed Jan. 4, 1974, Ser. No. 430,936

Term of patent 14 years

Int. Cl. D03—02

U.S. Cl. D61—1 A

FIG. 1

FIG. 2

FIG. 3

FIG. 4

FIG. 5

FIG. 6

FIG. 7

FIG. 1 is a front elevational view of a camera with a self-contained strobe light embodying my new design and showing the strobe light thereof disposed in an inoperative position.

FIG. 2 is a right-side elevational view of the camera of FIG. 1.

FIG. 3 is a left-side elevational view of the camera of FIG. 1.

FIG. 4 is a rear elevational view of the camera of FIG. 1.

FIG. 5 is a top plan view of the camera of FIG. 1.

FIG. 6 is a front elevational view of the camera with the strobe light thereof shown in an operative position; and

FIG. 7 is a right-side elevational view of the camera of FIG. 6.

I claim:

The ornamental design for a camera with self-contained strobe light, substantially as shown and described.
